ARTHUR HOSMER, OF CHICAGO, ILLINOIS.

COMBINATION TIE-PLATE AND RAIL-FASTENER.

1,134,455.

Specification of Letters Patent.

Patented Apr. 6, 1915.

Application filed August 23, 1913. Serial No. 736,276.

To all whom it may concern:

Be it known that I, ARTHUR HOSMER, a citizen of the United States of America, and a resident of Chicago, county of Cook, and 5 State of Illinois, have invented certain new and useful Improvements in Combination Tie-Plates and Rail-Fasteners, of which the following is a specification.

This invention relates to new and improved means for fastening the rails in railroad construction, both for street railways and for steam roads, and more particularly to rail holding tie-plates adapted to withstand the severe jarring and other destructive forces which are incident to the heavy 10 traffic now put upon most railroads and especially notable upon trunk lines.

Owing to increasing traffic, heavier rolling stock and a growing demand for greater 15 safety and higher economy in the maintenance, there is increasing need for more efficient tie-plates and rail fasteners.

The main objects of my invention are to provide an improved form of rail fastening 20 having a large gripping surface adapted to hold rigidly to the rail and not work loose in service; to provide an improved form of tie-plate adapted to receive different sizes of rails and adapted to prevent skewing of 25 the ties; to provide a tie-plate of improved form adapted to facilitate alining the rails and adjusting the gage of the track; to provide a tie-plate of this character which shall provide a broad bearing adapted to protect 30 and conserve the life of the ties, and adapted for efficient fastening to the ties; to provide an improved form of clamping and locking means for securing the tie-plates to 35 the rails, and adapted to compensate for the ordinary variations in rail width incident 40 to manufacture; to provide fastening means of the above character adapted for ready setting upon and release from the rail irrespectively of the tie; to provide an improved 45 form of locking means adapted for securing the fastening to the rail and adapted to positively prevent accidental release of the fastening; to provide complementary fastening means for the tie-plate arranged to 50 engage opposite flanges of the rail and adapted by mutual setting adjustment to aline the rails and gage the track; and to provide fastening means such as specified 55 which shall be strong, simple, and durable, and which may be either cast or rolled, or otherwise suitably formed.

A great portion of railway accidents are caused by defects either in track or rolling stock. With the present tendency to increase the weight and speed of cars and 60 trains, the track, as ordinarily constructed, is often strained beyond its limit of strength and wrecks are caused thereby. Of these track failures, the majority are caused either directly or indirectly by insecure fastening 65 of the rails, hence the need of improving upon the tie-plates at present in use, with a view to providing greater strength and security. The vast number of tie-plates necessary to equip a railway system obviously 70 requires that in order to be commercially practical the plate must be of absolutely simple and economical construction and use. It is these conditions and these requirements 75 that I have sought to meet.

The ordinary tie-plates now in use, and each usually consisting of a plain flat plate perforated for rail holding bolts, screws or spikes at points where the edges of the rail flange will come, are relatively weakened at 80 the critical points where the greatest strength is required. Hence such plates have to be made extra thick and heavy to resist bending at these points. In my improved plate, instead of holes which tend 85 to weaken the plate and render extra thickness necessary, I provide lugs on a relatively thin plate, which lugs tend to brace the plate at the edges of the rail, and strengthen rather than weaken it. Moreover, ordinary 90 plates offer no bracing to resist side thrusts and tipping of the rail, hence on curves it is customary to use separate braces at great expense. My improved plate on the other hand, when the lock and keys are in place, 95 assumes the character of a truss embracing the rail flanges and having a large flat bearing surface on its under side, and widely separated tie-engaging fastenings, thus constituting a broad and stable bearing to support and brace the rail independently of 100 any separate braces. When spikes or screws are placed adjacent to the flange of the rail, as with ordinary plates, the severe pumping action at this point tends both to break and to loosen them very rapidly, whereas by placing the spikes or screws at the outer ends of the tie-plates, as I have devised for my improved plate, the pumping action is 105 practically all spent in the spring of the tie and plate, and the spikes being well to one side of the rail are in large measure relieved.

- of the wear and tear. This saves frequent adzing of the ties and re-driving of spikes or screws and correspondingly decreases expense and increases the life of the ties.
- 5 Recent practice in heavy and expensive construction for street railway tracks, where the ties have been set in concrete and the rails welded together, has developed great difficulty in effectively securing the rails.
- 10 The lag screws by which the flanges are clamped to the ties pass through holes in the tie-plates used. These holes must be cast or punched in the plate for the standard gage used and no provision can be made for practical variations in the width of the rail flange. Hence, as ordinarily used, there is no certainty of the lag screws touching or engaging the edges or vertical sides of the flange of the rail, and bearing may be only at the point of contact of the head on the upper side of the flange. Moreover, the lag screws commonly used are manufactured with an umbrella head, and when the head is forced into engagement with the top of the flange of the rail only a point or extremely small surface under the head of the screw bears upon the rail, and this is soon worn off by vibration and the rail becomes loose. With my improved flange gripping tie-plate the lock piece grips the side of the flange of the rail with the full width of the plate, which may be about $5\frac{1}{2}$ inches, the key bears down on top of the flange of the rail for the same distance, and the lug on the opposite side about 3 inches, making about 14 inches of bearing or gripping surface engaging the rail. This large gripping contact provides a very secure and permanent bearing and prevents any movement or wearing loose. Experience has also shown that the lag screws as ordinarily used soon fail, the heads being broken or sheared off by the varying stresses and heavy side thrusts under the action of the heavier cars run at high speed. As soon as the rails become loose they are subject to creeping, and breaking is more frequent. My improved tie-plate is adapted for a most efficient distribution of an adequate number of holding screws or spikes. As the ties and fastenings are normally embedded in and covered by concrete, and paving, the importance of a reliable fastening is apparent.
- 55 In order to prevent rails from creeping, it has been customary in many cases to attach separate anti-creeping devices to the rail flanges, two for each of the rails, at their ends under the joints and two attached at or near the center of the rails for engaging the sides of the ties, the rails being arranged so that the joints on one side of the track come opposite the centers of the rails on the other side of the track. With my improved flange-gripping tie-plate I save the expense of separate anti-creeping fasteners by imparting this function to the tie-plates. By this means I provide for distributing the creep resistant force over all of the ties along the whole length of the rail.
- It is well known that a large proportion of steam railway accidents are caused by broken rails. Railway engineers and track experts are becoming convinced and agreed that the greater part of these failures are caused by crowding at the joints. It frequently occurs under ordinary construction that one or more rails become sufficiently loosened to permit slight creeping. When the advance of the creeping rail is arrested by butting against the end of an adjoining rail which is irresistibly secured, something is sure to give way. Either the rails will be thrown out of alinement, or one of them will break near the end, the latter usually occurring. By my improved rail gripping tie-plate I securely anchor each rail to every tie on which it rests and thereby prevent any of the rails from creeping or crowding. My improved fastening is so proportioned in its preferred form and size that the gripping area by which the rail is secured and held against creeping is substantially nine times as great as is afforded by ordinary spikes or screws in steam road construction. The binding and clamping effect is also more direct and positive. Creeping is thus prevented.
- The specifications for No. 1 steel T-rails permits $\frac{1}{16}$ of an inch variation in the width of the flange, but when the usual tie-plate is perforated for the rail holding spikes or screws no provision is made therein for this variation and the spikes or screws do not therefore ordinarily engage the sides of the flange of the rail. This is a serious defect, for the rocking motion of the train rapidly loosens the fastenings and the plate as ordinarily used. With my construction all variations in width of the rail flange are taken up by the revolving lock.
- On curves, it is ordinarily necessary to furnish separate braces to bear against the outside of the outer rail to prevent spreading of the rails or tipping thereof due to the centrifugal force of rapidly moving trains. By using my improved tie-plate the rail is prevented from spreading by the spikes or screws both on the inside and on the outside by the rail, and the rail is prevented from tipping by the broad bearing of the plate to which the rail is securely locked, and by the numerous and widely separated spikes or other tie engaging means by which the plate is fastened to the tie.
- On curves it is necessary to increase slightly the spacing between the rails. I provide for this, in one form of my improved tie-plate, (as in Figure 11) by lateral adjustment of the flange clamping means on the tie-plate without changing

the spacing of the tie-plates on the ties. This is important where steel or composition ties are used in order that uniform standard drillings for the tie-plate bolts or rivets may be used on all of the ties, and in order that the plates may be bolted or riveted to the ties at the factory or other convenient place before the ties are distributed along the track. I also contemplate providing wedge keys of different thicknesses for use in shifting, varying and adjusting the gage on curves, relatively thick keys being used on the inner side and thin keys being used on the outer side of the rail in order to increase the gage without any change in the position of the plates or any difference in the shape of the plates or lock pieces.

In order to lessen the cost of plates embodying certain of the principal features 20 of my invention, I contemplate forming the lug on one side of the plate to receive the flange of the rail direct, and forming the lug on the opposite side to receive my improved lock piece and wedge-key. This 25 form is adapted to serve on straight tracks and wherever the gage is uniform, and particularly where wooden ties are used.

As rolled metal work is stronger and cheaper than castings or forgings, I form 30 and arrange the parts of my improved tie-plate so as to facilitate rolling them in long lengths which may then be cut to size ready for use. In order to roll the lugs perfectly true on the plates and to avoid possible irregularities in the cylindrical inner surface 35 thereof, I first roll the bar in an inverted U-shape with the lugs rolled to their complete and final form thereon, and then straighten out the bar to its final flat form 40 by running through flattening rolls, after which it may be cut into tie-plate lengths. Bolt holes may be punched adjacent to the side edges after cutting.

Owing to the increasing scarcity of timber, wooden ties have to some extent been 45 and in all probability will in large measure be displaced by reinforced concrete and steel ties. The steel ties especially require insulation for the tie plates where the rails are used in signal circuits. In connection with 50 my improved tie-plate efficient means may readily be provided for securely attaching the same to the various kinds of ties, both where insulation is necessary and also where 55 none is needed, but insulation features form no part of this invention and are, therefore, not illustrated.

Attempts have been made to construct 60 practical rail-gripping tie-plates having lugs thereon to receive holding wedges arranged to be driven into place longitudinally of the rail directly between the said lugs and rail. Experience has generally shown, however, 65 that owing to the non-resilient and non-binding character of iron and steel under

these conditions, and the tendency of the wedges to jar loose under the great and changing side pressure and the powerful end thrusts, requires that such wedges in order to prevent creeping must be of very 70 slight angularity; that is to say, they must be extremely sharp and thin in order to hold and not jar loose quickly. In order to provide for variations in rail width and to enable proper alignment of the rails, it is 75 necessary that such sharp and thin wedges must be made extremely long. Experiments have shown that in order for wedges of this kind to bind securely they should be so formed as to drive approximately 3 inches for every $\frac{1}{16}$ inch of variation of rail width. These conditions tend to make the use of such a fastening not only insecure but too 80 awkward and cumbersome as well as wasteful of material. By my invention I use a 85 different system entirely, and use a locking key and a direct acting large-contact rotary clamping lock which longitudinal stresses and impacts do not tend to work loose.

The facility and speed with which track 90 secured by my improved fastening may be laid and taken up render the device especially useful in temporary track work, as where turn-outs and side tracks have to be installed to facilitate track renewals or track 95 elevation, and where temporary tracks are required, as to gravel pits, and also for movable tracks as in stone quarries and mines. Where my improved tie-plates are used the plates may remain spiked to the 100 ties and the rails readily released by simply withdrawing the wedge-keys as herein specified. The advantage of the labor saving feature is obvious.

Several illustrative embodiments of this 105 invention are shown in the accompanying drawings in which—

Fig. 1 is a perspective view of one form of my improved tie-plate and fastenings secured to a rail adapted for street railway 110 service. Fig. 2 is a central cross section through the right end of the tie-plate and adjacent rail flange shown in Fig. 1. Fig. 3 is an end elevation of the rotary lock member shown in Fig. 1. Fig. 4 is a rear elevation of the said rotary lock member showing the side having a leverage flange. Fig. 5 is a top plan view of said rotary lock member. Fig. 6 is a perspective view of a modified form of tie-plate and fastenings secured 115 to an ordinary T-rail adapted for use in steam railroad construction. Fig. 7 is a central cross section through the right end of the tie-plate and adjacent rail flange shown in Fig. 6. Fig. 8 is a rear elevation 120 of the rotary lock member shown in Fig. 6. Fig. 9 is a top plan view of the rotary lock member shown in Fig. 6. Fig. 10 is a front elevation of the wedge-key shown in Fig. 6 125 in its straight form ready for use. Fig. 11 130

is a central cross section of another modified form of tie-plate and fastenings and shows a rotary lock member on each side, one of which is shown with the wedge-key in place 5 and the other with the wedge-key not yet inserted.

In the construction shown in Figs. 1, 2, 3, 4, and 5 the tie-plate 1 comprises a substantially flat plate or base member 2 and a pair 10 of upwardly projecting inwardly curved integral lug members extending transversely across the face, symmetrically disposed and spaced apart for receiving the rail. One of these lugs 3 is formed to receive direct one 15 flange 4 of the rail 5, while the other lug 6 is of a modified form adapted to receive and coact with a clamping member or lock piece 7 disposed between the lug and the opposite flange 8 of the rail. The construction shown 20 in these figures is adapted for making from cast metal. The lug 6 is formed with an inner surface 9 of cylindrical shape through an arc sufficient to provide a suitable pivot or journal bearing for the lock piece or rotor 25 lock member 7, which has its front or outer surface 12 correspondingly shaped to fit within said lug. The said lock piece or jaw 7 on its opposite or inner side 13 is of a somewhat what concave or longitudinally grooved 30 shape, which side normally faces diagonally downwardly and backwardly toward the rail flange. The lower edge of the concave portion is formed to serve as a shoulder 15 adapted to abut squarely against the outer vertical edge of the rail flange in clamping 35 engagement therewith when the lock is set. The upper portion or flange 16 of the lock piece laps back over the rail flange 8 and is provided with a curved downwardly fac- 40 ing surface 17 forming part of the said inner side 13 of the lock piece. The surface 17 is preferably of a cylindrical arc shape and is adapted to receive and guide a complementary locking member or actuating wedge 45 key 20, which when driven into place between the rail flange 8 and the overlapping arm or leverage flange 16 of the lock piece rotates the latter upwardly and outwardly and forces the lower edge or shoulder 15 50 into gripping engagement with the rail flange 8. The key engaging flange 16 is formed so that its contact surface 17 is inclined lengthwise corresponding to the pitch of the wedge-key. The lock piece 7 is provided with a pair of transverse shoulders 22 and 23, one at each end, adapted and arranged to abut against opposite ends of the coacting tie-plate lug 6 to prevent longitudinal movement of the lock piece when in use. 55 The cylindrical back 12 of the lock piece is transversely hollowed or flattened somewhat along its middle portion 25 to facilitate downward or sidewise insertion of the lock piece into place between the rail flange 8 and the lug 6, said flattened portion or lug- 60

groove 25 being provided to permit the lock piece to drop past the tip of the rearwardly projecting lug 6 for assembling the fastening when the rail is in place. The wedge-key 20 is formed somewhat spike-shaped and 70 comprises a long narrow body and a head 21. The body is formed flat on its lower side to lie closely upon the rail flange and is curved substantially cylindrically on its upper side to fit the curved under side 17 of the leverage arm or flange 16. The head 21 is formed at the thick end of the wedge to prevent battering when the wedge is being driven into place and to prevent the wedge from going in too far as well as to facilitate withdrawal whenever realinement of the rails or other changes are necessary. The head 21 projects transversely of the body but the back side is flush with the flat back of the wedge. When the fastening is used for 80 securing a rail for street railway service as illustrated in Fig. 1, the tie-plate and fastenings are usually embedded in concrete which securely holds the wedge-key in place and prevents the key from backing out or working loose. Perforations 26 are provided in the widely separated opposite ends of the plate beyond the lugs for securing the tie-plate to the ties by any suitable means, as 85 spikes or lag screws. The upper portions of the lugs 3 and 6, shown in Fig. 1, do not extend quite to the opposite edges of the base-plate 2 but are formed with notched or recessed corners as shown at 27. By this construction the lock pieces need not project 90 beyond the edges of the plate 2, the shoulders 22-23 bearing against the inwardly disposed ends of the lug 6.

In the construction shown in Figs. 6, 7, 8, and 9, a slightly modified form and use of 105 tie-plate are illustrated, adapted especially for steam railroad construction. In this instance the plates 31 are formed and adapted for rolling instead of casting. The rail holding lugs 32 and 33 are formed to extend 110 across the full width of the tie-plate so that the plates may be rolled in long strips or bars and then cut off in suitable lengths to form tie-plates. With this construction the lock piece 35 is formed and adapted for in- 115 sertion lengthwise into place between the lug 33 and the rail flange 36 of a T-rail 37. In order to permit of such longitudinal insertion of the lock piece into the lug 33, one of the shoulders 38 on the lock piece is formed 120 to extend only a relatively short distance forward on the outer bearing surface 39 so that when the lock piece is turned back the shoulder 38 will pass freely by the tip of the lug 33 in assembling, but this shoulder 38 is 125 adapted to overlap and engage the end of the lug 33 when the lock piece has been rotated forward slightly as by action of the wedge-key 40 in clamping the fastening upon the rail. The opposite shoulder 41 is 130

preferably formed broad and full as shown in Fig. 6. In order to prevent any possible loosening or accidental withdrawing of the wedge-key 40, which in this instance is exposed while in service, the tip end is preferably bent up, the under side at the tip being beveled as at 42 to facilitate such upturning. Whenever it becomes desirable to release the fastening the tip may be readily straightened out and the wedge key withdrawn.

The form of lock piece shown in Figs. 1 to 5, having a pair of similar broad heavy shoulders, is especially adapted for single track roads where the traffic runs both ways over the rails and the end thrusts on the shoulders 22 and 23 due to tendency to creep and to train braking is substantially equal. In the case of one-way trunk lines, on the other hand, especially on steam roads, the thrusts are nearly all in the same direction and the lock piece stresses are nearly all thrown upon the head facing the approach. Hence in such service the lock piece shown in Fig. 6 is suitable, the narrow shoulder 38 being disposed upon the side from which traffic recedes. Obviously the lock pieces 35 may be made both right and left handed respecting the relative position of the shoulders 38 and 41. In all cases the lock piece is formed and arranged for the head of the wedge-key to lie adjacent to the large shoulder 41 and toward the train approach in order that creepage thrusts may always tend to drive the wedge more tightly into place.

In the modified construction shown in Fig. 11, the tie-plate 45 is formed with a pair of similar lugs 46 and equipped with a pair of corresponding similar lock pieces 47, one on each side of the rail. On the left side the lock piece is in position ready for insertion of a wedge-key. On the right side the wedge-key 48 is in place. By this construction the position of the rail may be varied laterally within certain limits for adjusting the gage by means of adjusting the wedge-keys. For instance, by partially withdrawing one of the wedge-keys and driving the other key in farther, the rail will be moved correspondingly in the direction of the first key, and vice versa. This gage adjusting construction, using a pair of complementary or differential fastenings, may embody either style of lugs and lock pieces shown in Figs. 1 and 6. The lugs are located symmetrically with respect to the center of the plate and are spaced apart sufficiently to readily permit downward insertion of the base of the rail into place therebetween. The bases of the lugs are all thickened and slope backwardly giving great stiffness and bracing strength both to the lugs and to the plate. This is true both of the flange engaging lugs or pocket lugs 3 and 32 and of the lock piece

lugs or fulcrum like pivot lugs 6 and 33. 65 As will be seen by referring to Fig. 2 the lug 6 constitutes a rigid pivot socket and the lock piece 7 constitutes a lever pivoted in said socket and comprising virtually two arms, namely, flange 16 and shoulder 15. 70

By driving a wedge-key into the space between the rail flange and the lock flange, I obtain a great turning leverage to set the lock for holding the rail tightly in place. Each wedge is preferably formed relatively 75 wide and flat in order to secure a broad and substantial bearing surface when it is driven into place.

In building new track the ties and plates may first be installed and then the rails may 80 be lowered into place with their flanges between the tie-plate lugs whereupon the locks may be set by driving in the wedge-keys and turning up the tips of the wedges. In repairing old tracks where wooden ties 85 are in use, the old plate will be removed, the new plate will be inserted between the ties beneath the rail and lifted up so that the rail flange will lie between the lugs, then the plate will be moved longitudinally 90 of the rail and slid into place on the tie whereupon the lock pieces may be inserted and locked by driving in the keys. The plate may then be bolted or spiked to the tie. If preferred the tie-plate may be secured to the tie before setting the lock. In order to disengage the tie-plate from the rail the wedge-keys are driven back and out and the lock pieces are removed leaving the rail free. 95

While I have herein shown and particularly described certain embodiments of my invention, it is to be understood that no effort has been made to illustrate all practical forms or uses, and it will be further understood that numerous details of the constructions shown may be altered or omitted without departing from the spirit of this invention as defined by the following claims. 100

I claim:

1. A combined tie-plate and rail fastening, comprising a base plate, opposing lugs thereon arranged to receive the base of the rail, a leverage member formed and adapted to coact between one of the lugs and the adjacent rail flange and having one part adapted to engage the edge of said rail flange and another part adapted to project over the said rail flange, and a wedge-key adapted to coact between the upper surface 115 of said rail flange and said projecting part to set the fastening, substantially as and for the purpose set forth.

2. A rail fastener comprising a tie-plate of substantially flat formation for seating a 125 rail thereon, coactive opposing means on the plate at opposite sides of the rail to receive and rigidly grip the base flange of the rail,

one of said means being arranged to engage the adjacent flange and powerfully force the rail laterally against the opposite means, the first of these said means comprising an 5 upstanding cylindrically curved lug, integral with the said plate and facing inwardly toward said adjacent flange, a substantially cylindrical locking bar fitting within the cylindrical inner surface of the said lug parallel 10 with the rail and formed with a longitudinal groove in its under side, one side of said groove being formed as a shoulder to engage the edge of the said adjacent flange, and a wedge key formed for wedging between 15 the said arm and adjacent flange to rotate said bar for forcing said shoulder tightly against the flange.

3. On a tie-plate, a rail flange fastening comprising an upstanding lug formed integrally with the plate and extending transversely thereupon and parallel with the position for the rail, said lug being cylindrically curved along its inner side facing toward the position for the rail, in combination 25 with a cylindrical locking bar formed to fit within the said lug between the inner surface thereof and the adjacent flange of the rail, and projecting somewhat beyond the ends of said lug, said bar being formed 30 with a longitudinal shoulder along its under side for abutting against the edge of the said adjacent rail flange, and with a projecting radial flange extending along the side thereof opposite from the said lug and 35 overlapping the said flange of the rail, said flange having a channel formed along its under side, and a wedge-key adapted to reciprocate within the said channel and adapted for driving inwardly between the flange 40 of the rail and the flange of the locking bar to rotate the latter to force said shoulder tightly into gripping engagement with the edge of the said rail flange.

4. In a holding device of the class described, a plate and a lug thereon cylindrically curved along one side and extending transversely of the plate, in combination with a locking member of substantially cylindrical shape on one side corresponding 50 with that of said lug, and adapted to rotatively oscillate therein, said locking member being suitably formed on the opposite side to engage the object to be held and having a leverage projection extending past the said object, and wedging means adapted for driving between the said object and the said projection to rotate the said locking member into its locking position.

5. In a rail fastener, in combination, a 60 rotary lock piece having a shoulder for engaging the edge of the rail flange, a rigid support for said lock piece and means bearing on the rail flange for forcibly rotating said lock piece in said support to set the said shoulder tightly against the rail.

6. In a rail fastener in combination, a rotary lock piece of substantially cylindrical shape and formed with a longitudinal groove and a flange on one side of said groove, a rigid seat arranged to oscillatably 70 support said lock piece parallel with the rail, said lock piece at one side of the groove being formed to receive the edge of the rail flange and said lock flange being formed to overlap the said rail flange, and a wedge 75 piece for driving between the said rail flange and said lock piece flange to rotate the said lock piece to tightly engage the said rail flange.

7. In a device of the class described, a 80 rotary lock piece having a cylindrical outer surface adapted to seat rotatably in a suitable support, and having a longitudinal groove along its under side to receive and abut against the edge of an adjacent rail 85 flange when the lock piece is duly rotated, and a lateral lever arm thereon arranged to overlap the said adjacent rail flange for rotating said lock piece when a reacting force is applied between said flange and 90 said arm.

8. In a rail fastener of the class described, a channeled rotary lock piece in combination with a bearing therefor and a wedge-key formed to reciprocate in a channel of 95 said lock piece to rotate the same.

9. In a rail fastener of the class described, a transversely channeled rotary lock piece in combination with a bearing seat and a controlling key formed to lie in a channel 100 of said lock piece.

10. In a rail fastener of the class described, a rotary lock piece in combination with a bearing therefor facing diagonally inward and downward toward the flange of 105 the rail and a wedge-key, said lock piece being formed with a downwardly projecting shoulder on its under side for engaging the edge of the rail flange and a laterally projecting shoulder extending inwardly over 110 the rail flange, and said wedge-key being formed to drive between the said laterally projecting shoulder and the rail flange to rotate the said lock for setting same with its said downwardly projecting shoulder 115 tightly against the rail.

11. In a fastener of the character described a substantially flat plate, an upstanding lug thereon cylindrically curved along one side, and extending transversely 120 of the plate, in combination with a clamping member partly of cylindrical shape corresponding with that of the said lug and adapted to rotatively oscillate therein, said clamping member being suitably formed on 125 one side to engage the object to be held and having an integral leverage projection extending past the said object, and wedging means adapted for driving between the said object and the said projection to rotate the 130

said clamping member into its holding position.

12. A railway tie-plate of substantially flat formation with a pair of opposing inwardly curved lugs formed integrally thereon and spaced apart to receive the base flanges of the rail therebetween, in combination with a pair of locking members each having a curved outer surface to fit within 10 said lugs for oscillatable mounting, and each formed with a shoulder to bear against the adjacent flange of the rail, and means to turn each of said locking members to force the said shoulders into gripping engagement with the rail flanges.

13. A railway tie-plate of substantially flat formation with a pair of opposing inwardly curved lugs formed integrally thereon and spaced apart to receive the base flanges of a rail therebetween, in combination with a pair of rotary locking bars formed to fit between said lugs and the said flanges of the rail, said locking bars each having a shoulder formed thereon to abut 25 against the adjacent edges respectively of the rail flange, and wedge-keys arranged to forcibly rotate said locking bars to force the said shoulders into gripping engagement with the rail flange.

30 14. In a rail fastener of the class described, a plate having a pair of fulcrum lugs formed integrally on its upper side to receive the base flange of a rail therebetween, and having bearing sockets therein, 35 leverage lock pieces having pivotal bearing, one in the socket of each of said lugs, said lock pieces each having a downward arm arranged to engage the edge of the rail flange and a lateral arm arranged to extend over 40 the adjacent rail flange, and wedging means adapted for driving tightly between the said flanges and the said adjacent lateral arms respectively for turning the said lock pieces forcibly in their sockets to grip the rail.

45 15. As an article of manufacture, a lock-piece consisting of a long narrow bar formed with a cylindrical outer surface on one side and having a longitudinal concave 50 surface on the opposite side, said concave surface being flanked by a shoulder on one side adapted to engage the edge of a rail flange, and a suitably curved shoulder on the opposite side adapted to retain a wedge 55 member, substantially as and for the purpose set forth.

16. As an article of manufacture, a lock piece consisting of a long narrow bar formed with a cylindrical outer surface on one side, and having a longitudinal concave surface on the opposite side, said concave surface being flanked by a shoulder on one side adapted to engage the edge of a rail flange, and a suitably curved shoulder

on the opposite side adapted to retain a 65 wedge member, said lock piece having transversely disposed shoulders projecting from said cylindrical surface at opposite ends, substantially as and for the purpose set forth.

70 17. As an article of manufacture, a lock piece consisting of a long narrow bar formed with a cylindrical outer surface on one side, and having a longitudinal concave surface on the opposite side, said concave surface being flanked by a shoulder on one side adapted to engage the edge of a rail flange, and a suitably curved shoulder on the opposite side adapted to retain a 75 wedge member, said lock piece having transversely disposed shoulders projecting from said cylindrical surface at opposite ends, and formed with said outer surface being between said shoulders, substantially as and for the purpose set forth.

80 18. As an article of manufacture, a lock piece comprising substantially a longitudinal body portion, and a pair of flanges having adjacent shoulders disposed substantially at right angles, said body member having transversely disposed opposing end shoulders, substantially as and for the purpose set forth.

85 19. As an article of manufacture, a lock piece comprising substantially a longitudinal body portion, and a pair of flanges having adjacent shoulders disposed substantially at right angles, said body member having transversely disposed opposing end shoulders, one of said opposing shoulders 90 being relatively narrow to facilitate longitudinal movement when the lock piece is turned on its longitudinal axis to a certain position, substantially as and for the purpose set forth.

95 105 20. In a device of the class described, a lock piece of generally cylindrical shape for rotative mounting in a suitable support, said lock piece having a longitudinal groove with one side substantially radial with respect to the axis of rotation and forming a shoulder, said lock piece having a lateral flange disposed longitudinally and extending radially therefrom at a position nearly quartering from the said shoulder and on the 110 side of said groove, opposite from said shoulder.

115 21. A rail fastening, comprising a tie-plate and lugs thereon to receive the base flanges of the rail, a lock piece disposed between one of said lugs and the adjacent rail flange, and a wedge key adapted for driving between said lock piece and the top of the rail flange to clamp the fastening upon the rail.

120 125 22. As an article of manufacture, a lock piece comprising substantially a longitudinal body portion, and a pair of flanges hav-

ing adjacent shoulders disposed substantially at right angles, the opposite side of said body portion being rounded, adapting it to serve as a rotary bearing, and one of 5 said adjacent shoulders being inclined somewhat from one end to the other, substantially as and for the purpose set forth.

Signed at Chicago this 18th day of August 1913.

ARTHUR HOSMER.
